UNITED STATES PATENT OFFICE.

JESSE R. OAKLEY, OF BRADDOCK, PENNSYLVANIA, ASSIGNOR OF ONE-HALF TO JAMES H. MULLEN, OF MONONGAHELA, PENNSYLVANIA.

COMMODE ATTACHMENT FOR WATER-CLOSETS FOR CHILDREN.

No. 806,176.

Specification of Letters Patent.

Patented Dec. 5, 1905.

Application filed January 4, 1905. Serial No. 239,621.

To all whom it may concern:

Be it known that I, JESSE R. OAKLEY, a citizen of the United States, residing at Brad-
dock, in the county of Allegheny and State of
5 Pennsylvania, have invented new and useful
Improvements in Commode Attachments for
Water-Closets for Children, of which the fol-
lowing is a specification.

My invention relates to certain improve-
10 ments in what may be styled "seat" or "com-
mode" attachments for water-closets for
children.

Said invention has for its object to readily
15 accommodate or adapt water-closets for the
use of children and to carry out this purpose
in a simple, expeditious, and effective man-
ner.

It consists of certain structural features
20 substantially as hereinafter fully disclosed,
and particularly pointed out by the claims.

In the accompanying drawings, illustrating
the preferred embodiment of my invention,
Figure 1 is a side elevation, and Fig. 2 is a
25 front elevation, of the invention or attach-
ment. Fig. 3 is a rear elevation, and Fig. 4
is an inverted plan view, thereof. Fig. 5 is a
folded or collapsed view of the same, and Fig.
30 6 is a broken-away view showing more par-
ticularly said attachment as when applied to
the outer edges of the closet bowl or hopper.

In the disclosure of my invention I provide
a seat or board 1, having the usual orifice or
opening 1^a therethrough for an obvious pur-
pose and which board has a back 2, suitably
35 hinged thereto and retained in its normal or
effective position by means of jointed or fold-
ing lateral braces 3, pivotally connected thereto
and to said seat. The hinging of said back
to said seat is effected, preferably, by the use
40 of triangular castings or plates 4, having
their horizontal portions secured laterally to
the former and their vertical portions in like
manner to the latter. At the forward end of
said seat or board 1 is applied a foot-rest 5,
45 suitably pivoted at its rear end to and so as
to fold in between lateral pendent bars or
suspenders 5^a, having upper angular forma-
tions 5^a, in turn pivoted at their extremities
to said seat, further later referred to. Said
50 foot-rest is upheld, as shown, by lateral jointed
braces 5^b, also pivoted near its forward
edge and to the suspenders 5^a upon their in-
ner sides at about their mid-lengths and are
adapted to permit the infolding of said foot-

rest when in collapsed condition. It will be 5^c
noted that the angular upper end portions 5^a
of the suspenders 5^a are laterally let into cut-
away portions or recesses 1^b of the seat or
board 1 at its forward edge and that the
shoulders 1^{bb} thus formed upon said board or 60
seat in rear of said recess are inclined down-
ward and rearward to accommodate the an-
gularity of said upper end portions, whereby
said suspenders are not only braced by the
contact of the latter with said shoulders, as 65
they are, but they are caused to stand later-
ally of and flank the top edge of the closet-
bowl, as indicated by Fig. 1, and thus serve
to guard against the lateral displacement of
the seat or attachment at its forward portion 70
when in position upon said bowl, as is appar-
ent.

Clamps (two sets) 6 7 are suitably applied to
and adjustable upon the under side of the seat
or board 1 near its rear edge and of the gen-
eral construction shown particularly in Fig.
75 3, being preferably of stiff strap metal and
conforming to the contour of the top edge or
"roll" of the closet-bowl, one set being ap-
plicable to the outer lateral surface thereof 80
and the other set to the inner corresponding
surface of the same, as seen in Figs. 3 and 6,
respectively, as may be desired, as presently
more fully explained. The adjustment of
said clamps is effected, preferably, by means 85
of longitudinal slots 6^a and 6^b, produced there-
in, respectively, and receiving set and hold-
ing screws 6^b and 6^c, engaging or working in
the seat or board 1 from its under side.

It is observed that in using said attachment 90
as a commode in connection with a water-
closet by preference the clamps 6 are initially
adjusted inward to enable the seat or board to
rest upon the roll or top edge of the closet-
bowl, after which said clamps are readjusted 95
to effectively engage the inner lateral edges
of the roll of the bowl at said edge, as dis-
closed especially by Fig. 3. At the same time
the foot-rest suspenders 5^a will assume such a
relation or position, as above noted, to the 100
closet-bowl top edge or roll as to stand later-
ally of the latter, and thus become effective to
guard the seat or board against lateral dis-
placement at that end.

As shown by Fig. 6, the clamps 7 may be 105
brought into requisition or service, if desired
or it should become necessary to make con-
nection with the outer lateral surfaces of the

closet-bowl roll. In that event the clamps 6 are removed and the clamps 7 are reversed or arranged so as to cause their hooked end portions to engage said outer surfaces of the 5 closet-bowl roll.

After use the attachment is removed from the closet-bowl and may be readily folded or collapsed into compact form or compass, as shown by Fig. 5, and be conveniently set aside 10 for future use.

Latitude is allowed as to details herein to permit changes thereof as circumstances may suggest without departing from the spirit of my invention.

15 I claim—

1. A child's commode attachment for water-closets, comprising a seat having applied to its appropriate surface, clamps adjustable with relation to, and adapted to clamp, the closet-bowl.

2. A child's commode attachment for water-closets, comprising a seat having applied to its appropriate surface, clamps adjustable with relation to, and adapted to clamp, either the 25 inner or outer lateral surfaces of the closet-bowl, at its top edge.

3. A child's commode attachment for water-closets, comprising a seat having applied to its appropriate surface two sets of clamps, adjustable with relation to the closet-bowl, at its 30 top edge, and adapted to engage the inner and outer lateral surfaces of the closet-bowl at its top edge, respectively.

4. An article of the character described, 35 comprising a seat having applied to its underside means for securing it to a closet-bowl, at its upper edge, and a foot-rest having sus-

penders provided with upper angular end portions connected laterally to said seat said seat having lateral recesses at its forward edge to 40 receive said suspender angular end portions for the purpose specified.

5. An article of the character described, comprising a seat having lateral recesses, at its forward edge, the shoulders formed by said 45 recesses having downward and rearward inclined surfaces, and a foot-rest having lateral suspenders provided with upper end angular portions connected laterally to said seat, within said recesses, and adapted to bear against 50 said inclined shoulders of the seat.

6. A child's commode attachment for water-closets, comprising a seat having applied to the appropriate surface thereof opposed clamps having normally outer downward-curved terminals, effective for engagement with the 55 closet-bowl upper edge and set-screws working in slots in said clamps.

7. A child's commode attachment for water-closets having applied to the appropriate surface thereof two sets of clamps, one set being arranged oppositely to the other set, and each set consisting of two clamp-bars having opposite downward-curved terminals effective to engage the inner and outer upper edges of the 60 closet-bowl, respectively, and set-screws working in slots of said clamp-bars.

In testimony whereof I affix my signature in presence of two subscribing witnesses.

JESSE R. OAKLEY.
